AMUSEMENT GAME

Edward P. Stein, Fulton D. Thornton, and Robert Morris, Chicago, Ill., assignors of one-half to John A. Russell, Chicago, Ill.

Original application December 28, 1934, Serial No. 759,538. Divided and this application April 13, 1937, Serial No. 136,560

10 Claims. (Cl. 273—119)

Our invention relates to improvements in an amusement game of the ball projecting type having a playing board inclined or sloped from the horizontal so that balls may gravitate down the same into holes formed through the board to trap the balls. The present application is a divisional application of our copending application Serial Number 759,538, filed December 28, 1934 for Amusement game. These holes may have certain values to encourage skill and competition among several players. For instance, in the form of the game herein to be disclosed, it is intended to simulate the well known card game of poker in which five cards are drawn. Accordingly, the holes in the preferred embodiment of our game are given designations corresponding to those used in a deck of playing cards. When a projected ball is trapped by a hole the ball moves down an under guide as covered in our said copending application, to set and hold in place a register having thereon a card value designation corresponding with that of the hole which received the ball. Obviously, in such game it is not desirable to trap more than one ball in each hole and therefore we provide each hole with a normally open check or trap door hingedly mounted in the holes and having a trip leg portion formed therewith to receive the ball dropping through the hole to hinge or pivot the trap door or check to hole closing position.

The primary object of our invention is to provide a ball closed trap door for the holes in the game board.

Still another very important object is to provide a coin released shiftable or other movable means for resetting the trap doors to hole uncovering position.

Other important objects will no doubt be apparent to those skilled in this art.

40 In the accompanying sheets of drawings:

Figure 1 is a general plan view of the amusement game;

Figure 2 is an enlarged side sectional view through the game taken along the line 2—2 of Figure 1, looking in the direction of the arrows;

Figure 3 is an enlarged detail plan view of the under shiftable mechanism for resetting the trap doors, the view being taken along the line 3—3 of Figure 2 looking downwardly;

Figure 4 is an enlarged front view of the novel trap door structure, seen partly in section and viewed along the line 4—4 of Figure 5;

Figure 5 is a longitudinal, enlarged, detail sectional view through a ball trap and hole taken along the line 5—5 of Figure 1;

Figure 6 is a detail cross sectional view through the guide between the top board and guide or alley panel as seen along the line 6—6 of Figure 5 to show its cross sectional contour; and,

Figure 7 is a similar sectional view of the same 5 guide taken along the line 7—7 of Figure 5.

As shown in Figures 1 and 2 the game is housed in a box 15 having a front wall 16, the box, or cabinet being closed at its top by a glass panel 17. The game board is shown at 18 the same being 10 sloped from the horizontal with its low end toward the front wall 16. At the right hand side of the board 18 is a ball projection passage 19 and at the front end thereof is a manually operable ball projector 20 carried in the front wall 16. The upper end of the board 18 is formed with an arcuate track piece 21 to lead the projected balls to a cushion 22 from which the balls rebound to gravitate down the board 18. Across the lower edge of the board 18 is a transverse partition 23 having 20 inclined rear edges to cause a ball rolling thereto to be led to a central hole 24 to drop there-through and be caught by a shallow transverse inclined trough 25 which leads such balls back into the passage 19 to gravitate back into position 25 to be rolled over again by the projector 20. This gives the player a free play of all balls missing the main holes arranged over the game board.

Forwardly of the lower end of the board 18 between the partition 23 and front wall 16 is a 30 cover plate 26. As shown in Figures 2 and 3 a cross plate 29 is slidably mounted on supports or tracks 30 carried by the side walls of the cabinet beneath the plate 26. This plate 29 is secured at 31 to a conventional form of coin released slide 32 35 so that when the slide is moved the plate 29 and all structure connected therewith moves also.

Below the plate 26 the cabinet in any desired way carries a U-shaped ball receiving trough 39 the parallel runs of which are reversely inclined 40 in a transverse direction. Balls, as will later be described falling into the rear run (which is the one remote from the front wall 16), roll by gravity to the left-hand side of the cabinet, thence around the bight portion and finally into the other or 45 rear run of the trough to gravitate toward the right-hand side of the cabinet where a suitable lifter, indicated at 40 is disposed for elevating the balls into the lower end of the passage 19 for projection onto the board 18 by the shooter 20 50 as disclosed in our copending application mentioned.

Scattered over the board 18 and formed there-through are a number of ball drop holes 55, each said hole being half rounded at their rear ends 55

to receive the balls and formed with parallel longitudinal side edge portions toward their forward ends by notching out the board as at 56. The holes are so shaped, each to receive a tubular and 5 U-shaped depending ball guide 57 which as shown in Figures 4, 5 and 2 are each slotted vertically at their front edge and spread apart to form parallel sides 58 to fit the notched hole 55. These sides 58 in each hole 55 include upstanding ears 10 59 to carry a pivot pin 60 for hingedly mounting a trap door 61 having wings 62 for normally resetting the doors on the board 18 as shown in Figure 5 in hole opening position. The door is so held by its own weight.

15 Further each door includes a trip leg 63 extending angularly from the door 61 and normally in a position within the hole 55 to obstruct the same so that a ball entering the hole must engage the leg 63 to pivot the door 61 downwardly to hole 20 closing position in an obvious manner. Each guide 58 is U-shaped at 58 as shown in Figure 6, in cross section, and has its lower end cut off at an angle as at 64 to provide another U-shaped cross section as shown in Figure 7.

25 A ball dropping through any hole 55 closes the trap door 61 and then drops down through the board 18 onto a guide or alley member made up preferably of a number of channel members which may be half round pipe-like sections 65 arranged 30 in parallelism side by side and welded together to form an alley panel stationarily mounted on the walls of the cabinet as shown in Figure 2. There is one such lengthwise groove or alley 65 under each hole 55 and the guides 57 are U- 35 shaped properly to direct each falling ball with certainty onto its alley 65, said guide members 57 being associated with the alley panel 65 between it and the top board 18. It is noted that each alley or groove 65 guides a ball onto the alley board 53 40 which has aligned grooves or tracks as heretofore described.

Slide bars 35 at their rear ends are connected by a cross bar 66 which carries a number of push rods 67 there being one over each groove 65 and 45 one for engaging the leg 63 of each trap door 61. These rods are of different lengths as the holes 55 are differently spaced lengthwise along the board 18. When the slide 32 is moved everything connected thereto is also moved, such for example as 50 the plate 29, bars 35, 66 and rods 67.

The game board 18 on its top surface may be ornamented by card designations such as the diamond, spade, club, and heart, shown, and each hole 55 may be appropriately marked to show the 55 various cards in each suit to make possible the playing of a simulated poker card game, as has been stated.

In playing the game the balls are raised by the lifter 40, one at a time, from the lower end of the 60 trough 39 into position in back of the projector 20 in the passage 19, which at its front end is preferably depressed below the level of the board 18. When the balls are so projected, they gravitate from the high end of the board 18 downhill, 65 and possibly into the holes 55, wherein the trap doors, or checks 61 are in hole uncovering position. As a ball drops through a hole 55 it presses down on the leg trip 63 of the door to pull the same downwardly to hole closing position so that only 70 one ball, during a game cycle can drop through a given hole. Each hole will have some card designation such as king of clubs, queen of spades, etc., which marking may, if desired, be placed on each door check 61.

75 The ball dropping through the hole as described

is definitely guided by the member 57, which is U-shaped in cross section, onto a guide alley 65 to permit the ball to roll down the same and into the trough 39.

When the game cycle of play is over, the coin 5 chute or slide 32 is operated to push the bars 29, 66 and rods 67 rearwardly (away from the front wall 16) causing said rods to engage the legs 63 of all closed doors 61 to raise same to their hole opening positions in an obvious manner.

It is the intention to cover all changes and variations of the example of a game structure herein selected for purposes of illustration which do not depart from the spirit and scope of our invention as hereinafter claimed.

What we claim is:

1. A game of the ball projecting type having an inclined game board provided with a hole therethrough to receive a ball, said board at the hole being cut out to provide a notch presenting 20 parallel side edges, a normally vertically disposed trap door arranged over the board including hinge means in the notch for connecting the trap door to the board, said door including a trip arm extending normally into the hole to receive a 25 dropping ball to close the trap door with respect to the hole, and slidable means arranged below the board to engage the trip arm for moving said door back to its vertical hole opening position.

2. A game of the ball projecting type having 30 an inclined game board provided with holes therethrough, a movably mounted closure member adjacent each of said holes and having portions operable by balls dropping through said holes to move the closure members to hole closing 35 positions, and means movably carried below the game board for resetting said closure members into hole opening positions.

3. A game of the ball projecting type having an inclined game board down which balls may 40 gravitate, said board provided with holes through which balls may drop, an inclined guide member having spaced channel alleyways located under the board, and said alleyways having ends terminating substantially under the holes and 45 having U-shaped guides located between the board and guide member and surrounding the terminal ends of the alleyways to guide the balls dropped through the holes into the alleyways.

4. An amusement game having a board over 50 which a ball may be rolled to drop into a hole formed therethrough, a pivoted trap door for the hole normally arranged substantially vertically but movable to a hole closing position, the trap door including an angularly related leg normally 55 located in the hole to be engaged by a ball dropping into the hole whereby to pivot the door to a position closing the hole.

5. An amusement game having an inclined board over which a ball may roll to be caught 60 by holes formed through the board and through which a ball may drop, a second inclined member under the board and comprising alleys the ends of which lie substantially under the respective holes, a guide under each hole to direct dropping balls onto the alleys, a ball closed trap door for each hole, and shiftable means between the board and member to reopen the trap doors.

6. An amusement game having an inclined board over which a ball may roll to be caught 70 by holes formed through the board and through which a ball may drop, a second inclined member under the board and comprising alleys the ends of which lie substantially under the respective holes, a tubular guide carried in each hole 75

and extending therebelow to direct dropping balls onto the alleys, said guides pivotally carrying ball closed trap doors for the holes which doors include trip arms, and shiftable means movable into the guides to reset the doors to hole opening position.

7. The combination with a game board over which a ball may be projected to drop into a hole formed therein of a hinged door for the hole and normally disposed substantially vertical but movable to hole closing position, said door having a substantially right angularly disposed trip arm secured thereto and normally located to receive the ball dropping through said hole for moving the door to hole closing position.

8. A ball projecting game comprising an inclined panel formed with a hole to receive a ball, a door hingedly mounted adjacent the hole, and normally upstanding above said panel, said door having a trip arm engageable by balls passing through said hole for moving said door to hole closing position, and slidale means below the board to engage the trip arm for moving said door to hole opening position.

9. The combination of an inclined board down which balls may gravitate, said board having holes therethrough through which balls may pass, of a second inclined board under the first board, said second board having alleyways whose ends at one end terminate substantially under the respective holes, and a U-shaped wall adjacent the said terminal ends of the alleyways to guide the balls dropped through the holes into the alleyways.

10. In a game apparatus, combination of: a member providing a playing surface and having ball exit openings therein; a movably mounted closure member adjacent to each of said ball exit openings and operable by balls passing therethrough to close said openings; and movably mounted means carried below the playing surface member for resetting said closure members into open position so as to open said ball exit openings.

EDWARD P. STEIN.
FULTON D. THORNTON.
ROBERT MORRIS.
